CLAIM

The ornamental design for a motorcycle body, as shown and described.

DESCRIPTION

FIG. 1 is a right side elevation view our motorcycle body shown mounted on a motorcycle frame, the motorcycle wheels and frame in broken lines, showing our new design; FIG. 2 is a left side elevation view of the motorcycle body of FIG. 1;

FIG. 3 is a front elevation view of the motorcycle body of FIG. 1;

FIG. 4 is a rear elevation view of the motorcycle body of FIG. 1;

FIG. 5 is a top plan view of the motorcycle body of FIG. 1;

FIG. 6 is a bottom plan view of the motorcycle body of FIG. 1; and,

FIG. 7 is a top, front, right perspective view of the motorcycle body of FIG. 1.

The broken lines showing portions of a motorcycle in FIG. 1, and showing portions of the motorcycle body in other figures, are included for the purpose of illustrating unclaimed environment and unclaimed features and form no part of the claimed design.

1 Claim, 6 Drawing Sheets
